UNITED STATES PATENT OFFICE

135,298

DESIGN FOR A COMBINATION FIRE SCREEN AND SEAT

Robert L. Cook, Dallas, Tex.

Application December 30, 1942, Serial No. 109,165

Term of patent 7 years

To all whom it may concern:

Be it known that I, Robert L. Cook, a citizen of the United States, residing at Dallas, in the county of Dallas and State of Texas, have invented a new, original, and ornamental Design for a Combination Fire Screen and Seat, of which the following is a specification, reference being had to the accompanying drawing, forming part thereof.

Figure 1 is a front elevation of a combination fire screen and seat, showing my new design.

Figure 2 is a rear elevation thereof.

Figure 3 is a top plan view.

Figure 4 is a side elevation.

I claim:

The ornamental design for a combination fire screen and seat, as shown.

ROBERT L. COOK.
